UNITED STATES PATENT OFFICE.

JOSEPH NOVIN, OF NEW YORK, N. Y., ASSIGNOR TO THE CENTRE LIGHTING FIXTURE MFG. CO., OF NEW YORK, N. Y., A PARTNERSHIP COMPOSED OF SAID NOVIN AND SAMUEL RIBAK.

DESIGN FOR A CHANDELIER.

Application filed May 21, 1928. Serial No. 26,781. Term of patent 3½ years.

To all whom it may concern:

Be it known that I, JOSEPH NOVIN, of the city of New York, county of Bronx, and State of New York, have invented a new, original, and ornamental Design for a Chandelier, of which the following is a specification, reference being had to the accompanying drawing, forming a part hereof.

The drawing shows a perspective view of the chandelier which has arms for the support of candles or drop lights.

I claim:

The ornamental design for a chandelier substantially as shown and described.

JOSEPH NOVIN.
